UNITED STATES PATENT OFFICE

FRANK SMITH, OF CINCINNATI, OHIO

DESIGN FOR A DISPLAY RACK FOR GOLF BAGS AND CLUBS

Application filed January 2, 1931. Serial No. 38,188. Term of patent 7 years.

To all whom it may concern:

Be it known that I, FRANK SMITH, a citizen of Canada, and a resident of Cincinnati, in the county of Hamilton and State of Ohio, have invented a new, original, and ornamental Design for a Display Rack for Golf Bags and Clubs, of which the following is a specification, reference being made to the accompanying drawing, forming part thereof.

Fig. 1 is a side view of a display rack for golf bags and clubs showing my new design. Fig. 2 is a top view, and Fig. 3 an end view of the same.

I claim:

The ornamental design for a display rack for golf bags and clubs as shown.

FRANK SMITH.
